MOSES A. JOHNSON, OF LOWELL, MASSACHUSETTS.

Letters Patent No. 65,814, dated June 18, 1867.

IMPROVED CARPET-LINING.

The Schedule referred to in these Letters Patent and making part of the same.

TO ALL WHOM IT MAY CONCERN:

Be it known that I, MOSES A. JOHNSON, of Lowell, in the county of Middlesex, and State of Massachusetts, have invented a new and useful improvement in Carpet-Lining; and I do hereby declare the following to be a full, clear, and exact description of the same, reference being had to the accompanying drawings, making a part of this specification, in which—

Figure 1 represents a portion of the fabric, sufficient to fully understand its mode of manufacture.

My invention consists in an article of manufacture as a lining for carpets, or, for, as it is sometimes termed, a pad or sub-carpet, composed of felted hair or other material, and strengthened by strips of paper, or similar fibrous or textile fabric, to give it strength, and a free escape for the dust and dirt to pass through to the floor.

To enable others skilled in the art to make and use my invention, I will proceed to describe the same, with reference to the drawings.

A represents a bat of felted hair, or of which felted hair is the principal ingredient. This bat may be of any suitable width and length and thickness, and may be made moth-proof. Upon one or both sides of this bat A I paste cement, or sew strips B of paper, or other fibrous or textile material, to give additional strength and body to the fabric, and for the further purpose of allowing the dirt and dust to pass through the bat on to the floor.

I prefer to use felted hair for the pad, as being cheap and durable, and readily made moth-proof, but may mix with it other material used for the purposes of carpet-pads, or use such other material without the hair, such as wool, cotton, or similar fibrous material.

Having thus fully described my new article of manufacture, I would state that I am aware that a felted hair bat or pad is not new, and further, that it is not new to cover such a bat or pad on one or both of its sides with paper, and these I lay no claim to; but what I do claim as a new article of manufacture, is a felted hair-bat, or its equivalent, covered with strips of paper on one or both of its sides, and leaving intervening uncovered spaces between the strips for the dust to pass through, as herein described and represented.

MOSES A. JOHNSON.
